John L. Richardson

ATTORNEY.

UNITED STATES PATENT OFFICE

LED L. RICHARDSON, OF CLEVELAND, OHIO, ASSIGNOR TO THE CLEVELAND ROCK DRILL COMPANY, OF CLEVELAND, OHIO

HOLE-CLEANING VALVE FOR ROCK DRILLS

Application filed August 21, 1928. Serial No. 301,067.

The present invention is directed to improvements in hole cleaning valves for rock drills.

The primary object of the invention is to provide a device of this character so constructed that either water or motive fluid can be conducted through the fluid conducting tube for cleaning cuttings from the drill hole.

Another object of the invention is to provide a device of this kind wherein a valve is employed capable of being rotated in reverse direction in order that water or air can be selectively used for removing the cuttings from the hole being drilled.

Another object of the invention is to provide a device of this character so constructed that a unitary device is produced wherein a drill equipped with the device can be used wet or dry as the occasion may require, the construction being extremely simple and compact, durable, efficient in operation, and one which can be manufactured at a small cost.

With these and other objects in view, as will appear as the description proceeds, the invention accordingly consists in the novel features of construction, combination of elements and arrangements of parts, hereinafter to be fully described and pointed out in the appended claims.

In the accompanying drawing, in which similar characters of reference denote like and corresponding parts throughout the several views thereof:—

Figure 1 is a sectional view showing the valve in position for utilizing the motive fluid for blowing a hole.

Figure 2 is a view showing the valve in position for blowing or cleansing the hole with water.

Figure 3 is an end view of the valve controlling handle.

Referring to the drawing, 1 designates the back head of a drill which is coupled to the cylinder 2 in the customary manner and has movable therein the piston hammer 3, and into which extends the usual rifle bar 4, said bar and hammer having alined bores 5 and 6, respectively, and in which extends the fluid conducting tube 7. The back head is provided with a chamber 8, threaded for a por-

tion of its length, as at 9, said chamber being in communication near its upper end with the water inlet passage 10 through a passage 11. The lower end of the chamber is connected with the motive fluid passage 12 by a passage 13.

A plug 14 is employed and is threaded in the chamber 8, said plug having a reduced extension 15 upon its lower end and in which is formed a seat 16, the purpose of which will be later explained. The fluid conducting tube 7 extends into the chamber 8 and has its extended end engaged in the packing elements 17 and upon which the extension 15 rests to assure a fluid tight connection. The flanged end of the tube 7 is accommodated in the seat 16. The plug 14 is formed with an axial bore 18 which opens at its lower end into the seat 16. Rotatably mounted in the bore 18 is a stem 19 having a head 20 upon its lower end for rotatably engaging the seat 16, said stem having conduit 21 formed longitudinally therein and closed at its upper end, as at 22, while the lower open end thereof opens through the head 20 and is alined with the upper end of the tube 7. Opening into the conduit 21 are upper and lower ports 23 and 24 which are adapted to be alternately brought into registration with the ducts 25 and 26 formed in the wall of the plug 14.

The upper end of the stem extends above the head 27 of the plug and is recessed at 28. Riveted to the extended end of the stem is a handle 29 having mounted therein a spring pressed plunger 30 adapted to selectively engage the sockets 31 and 32 formed in the base of the recess 28 to hold the stem in adjusted positions. By providing the recess 28 angularly disposed shoulders 33 are provided and serve to limit the swinging movement of the handle 29 in order that the plunger 30 will engage the sockets 31 and 32 in order to hold the respective ports 23 and 24 in registration with the ducts 25 and 26.

As shown in Figure 1 the plunger 30 is engaged in the socket 32, thus holding the stem with its port 24 in registration with the duct 26 in order that motive fluid flowing from the passage 13 will enter the conduit 21 and pass therethrough into the tube 7 for blowing the

cuttings from the drill hole. Obviously when the handle is swung in a reverse direction the port 24 will move out of registration with the duct 26 thus cutting off the flow of motive fluid, whereupon the port 23 will be brought into registration with the duct 25 in order that water flowing from the passage 11 will pass into the conduit 21 and from thence into the tube 7 for cleansing the hole with water when desired.

10 What is claimed is:—

1. The combination with the back head of a drill having a chamber therein, of a plug fitted in the chamber, a stem rotatable in the 15 plug and having a conduit therein, a fluid conducting tube, communicating with the conduit, said back head having motive fluid and water passages therein, and means carried by the plug and stem for selectively 20 conducting fluid from the respective passages to the tube, as and for the purpose set forth.
2. The combination with the back head of a drill having a chamber therein, of a plug fitted in the chamber and having an extension 25 upon its lower end provided with a seat, a stem rotatable in the plug, said stem having a conduit, one end being closed and the other end opening into the seat, a fluid conducting tube having its upper end located in the seat 30 and alined with the conduit, said back head having a water passage and a motive fluid passage therein, means for conducting fluid from the respective passages to the chamber, co-operative means for selectively conducting 35 either water or motive fluid to the conduit to be directed into the tube, as and for the purpose set forth.
3. The combination with the back head of a drill having a plug fitted therein, of a stem 40 rotatable in the plug, said stem having a conduit therein, a fluid conducting tube alined with the conduit, said plug and stem having ducts and ports, respectively, said back head having water and motive fluid passages therein, and communicating with the ducts, and 45 means for rotating the stem to alternately cause registration of the ports and ducts.

In testimony whereof I affix my signature.

LED L. RICHARDSON.
